UNITED STATES PATENT OFFICE.

ELLIOTT R. BARKER, OF BERLIN, NEW HAMPSHIRE.

APPARATUS FOR THE MANUFACTURE OF BISULFITE LIQUORS.

No. 818,811.

Specification of Letters Patent.

Patented April 24, 1906.

Application filed October 21, 1905. Serial No. 263,787.

To all whom it may concern:

Be it known that I, ELLIOTT R. BARKER, a citizen of the United States, residing at Berlin, in the county of Coos and State of New Hampshire, have invented new and useful Improvements in Apparatus for the Manufacture of Bisulfite Liquors, of which the following is a specification.

This invention relates to an apparatus for the manufacture of bisulfite liquors, the object of the invention being to provide a cheap, simple, and efficient device for the purpose set forth in which a uniform distribution of gas throughout the liquors employed is secured.

The invention consists in the combination and arrangement of parts set forth in the following specification, and particularly pointed out in the claims thereof.

Referring to the drawings, Figure 1 is a vertical longitudinal section, partly in elevation, of my improved apparatus. Fig. 2 is a plan section taken on line 2 2 of Fig. 1 looking downwardly in said figure.

Like numerals refer to like parts throughout the several views of the drawings.

In the drawings, 5 is a vertical cylindrical tank, in which 6 is the cylindrical wall, 7 the top, and 8 the bottom, thereof. The interior of said tank is divided into four compartments 9, 10, 11, and 12 by a plurality of partitions 13, 14, 15, and 16. Each of said partitions is provided with a large number of perforations 17, preferably of conical formation, with the smaller ends opening through the upper surface of each of said partitions. The lowermost partition 16 is located at a distance from the bottom 8 of said tank substantially less than the height of any of the compartments 9, 10, 11, and 12 and forms a gas-distributing chamber 28, which is connected by a pipe 18 to gas-coolers (not shown) constituting receptacles for the gas which is used in the manufacture of the bisulfite liquors, as hereinafter set forth. The pipe 18 projects out of the bottom 8 of the tank, extending radially outward therefrom, and then projects upwardly to a sufficient distance to prevent any liquid which may be in the tank from flowing through said pipe into the gas-receptacles when the apparatus is shut down.

The compartment 9 is connected to the compartment 10 by an overflow-pipe 19. The compartment 10 is connected to the

compartment 11 by an overflow-pipe 20. The compartment 11 is connected to the compartment 12 by an overflow-pipe 21, and an overflow-pipe 22 leads out of the compartment 12 to an acid-well. (Not shown in the drawings.) Said pipe 22 is provided with a shut-off valve 23. An exhaust-pipe 24 leads out of the upper compartment 9 to a vacuum-pump. The liquid (in this instance milk of lime) is supplied to the tank through the supply-pipe 25, said supply-pipe being provided with a shut-off valve 26.

A rotary shaft 27 extends downwardly through the different compartments from the top to the bottom of the tank and is journaled to rotate in a bearing 29, fast to the top 7 of the tank, and in a stepped bearing 30, fast to the bottom 8 of the tank. Agitator-blades 36 are fastened to said shaft 27 at different points throughout its length, one set 75 of agitator-blades 36 being supplied for each of the compartments 9, 10, 11, and 12. Rotary motion is imparted to said shaft 27 by a bevel-gear 31 and bevel-pinion 32 meshing therewith, said bevel-pinion being fastened to 80 a shaft 33, journaled to rotate in bearings 34 and 35 and rotated by means of a pulley 35.

The operation of my improved apparatus hereinbefore specifically described is as follows: Assuming the apparatus to be empty 85 and that it is to be started for the first time, the vacuum-pump is started and gas is supplied to the interior of the tank through the pipe 18, the same flowing into the gas-distribution chamber and passing upwardly 90 through the perforations 17 in the partitions 16, 15, 14, and 13 and into the compartments 12, 11, 10, and 9 consecutively. It being understood that the gas is now passing through the different compartments 9, 10, 11, and 12 95 through the perforations 17, the valve 23 is first closed and the valve 26 opened, allowing liquor—viz., milk of lime—to flow through the pipe 25 into the compartment 9 until said milk of lime arrives at the height of the line *a* 100 in said compartment. The supply still continuing to flow in through the pipe 25, said liquor will pass through the overflow-pipe 19 into the compartment 10 until it fills said compartment to the height of the line *b* 105 therein. Then overflowing, said liquor will flow through the overflow-pipe 20 into the compartment 11 until it reaches the height of the line *c*. Overflowing again, said liquor will flow into the compartment 12 until it 110

reaches the height of the line *d*. While the apparatus is being filled with the liquor, as hereinbefore set forth, it will be understood that the shaft 27 and the agitators 36 are being rotated by means of the mechanism hereinbefore described. As soon as the levels *a*, *b*, *c*, and *d* in the different compartments have been reached by the lime-water, as hereinbefore described, the lime-water is shut off until 5 the acid becomes clear in the lowermost compartment 12. This shows that all the milk of lime has been converted to bisulfite of lime and that there is an excess of free sulfuric acid. As soon as this occurs the valve 23 is 10 opened and also the valve 26 to allow lime-water to flow into the upper compartment to compensate for that which flows out through the pipe 22 to the acid-well, and these valves are so regulated that the outflowing finished 15 liquor which flows out through the pipe 22 shall be of the required strength.

During the process hereinbefore described it will be understood that gas is supplied through the pipe 18, the same flowing into 20 the gas-distribution chamber 28 and passing upwardly through the perforations 17 in the partition 16 through the liquor contained in the compartment 12, then upwardly through the perforations in the different partitions 15, 25 14, and 13 consecutively and through the compartments 11, 10, and 9 consecutively. After arriving in the upper compartment it is drawn off by means of the exhaust-pipe 24 and an exhaust-pump attached thereto. The liquor 30 travels continuously from one compartment to the next lower, and the volume of liquor thus overflowing is always kept equal to the volume of lime-water entering through the pipe 25.

35 40 As soon as the vacuum-pump is shut down the valve 23 is closed and the liquor from the different compartments flows through the perforations 17 in the different partitions until it comes to rest at a level substantially 45 equal in height to the sum of the different depths of liquor contained in the four compartments. At this time in the operation of the machine the liquor will rise in the gas-inlet pipe 18 to the same level that it assumes 50 in the interior of the tank 5, and to prevent the liquor from flowing back to the gas-coolers when the apparatus is shut down said pipe 18 is extended vertically from the bottom of the tank to a distance greater than the height of 55 liquor referred to.

In starting the apparatus after it has been 60 shut down, as hereinbefore described, the vacuum-pump is started, and when the liquor has become clear in the lower compartment 65 by reason of the gas passing through said liquor from the supply-pipe 18 and upwardly therefrom through the tank the valve 23 is opened and lime-water admitted through the supply-pipe 25, as hereinbefore described, 65 keeping the level of the liquor in the different

compartments at the same heights as hereinbefore set forth—viz., at the height of the lines *a*, *b*, *c*, and *d*, respectively.

The advantage of my improved apparatus for the manufacture of bisulfite liquors is as follows: First, the perforated partitions supply means for obtaining a very uniform distribution of gas throughout the liquors contained in the different compartments. These perforations being small break the gas up into small bubbles or globules, thereby obtaining better absorption by the lime-water contained in said compartments. The small size of the bubbles also makes it possible to obtain very strong solutions of bisulfite liquors. The combined area of the perforations is sufficient to allow free passage of gas with a minimum loss due to friction. The provision of four compartments tends to insure the efficiency of the apparatus, for practically all the absorption will take place in the three lower compartments, while the upper compartment will serve as a guard against any sulfur-dioxide gas escaping.

Another advantage secured by the construction hereinbefore described is that the large number of small perforations uniformly distributed over the perforated partitions supplies a very efficient method of agitation to the liquors contained in said compartments. This agitation starts at the very bottom of the body of liquor in each compartment, thus giving such a perfect agitation that there is practically no quiet area in which monosulfite of lime or dirt or other troublesome compounds can settle or accumulate. The matter of the perforated partitions hereinbefore referred to, by means of which a perfect agitation and distribution of gas in small bubbles throughout the different compartments and throughout the liquors contained therein are secured, is a very important one in an apparatus of the class hereinbefore described, and it is my intention in many cases to operate the apparatus without the agitators 36—simply by the distribution of gas in small bubbles, as hereinbefore described, throughout the body of the liquor contained in the different compartments and forcing said gas through the said liquor by the use of the suction-pump connected to the upper compartment 9 by the pipe 24.

Having thus described my invention, what I claim, and desire by Letters Patent to secure, is—

1. An apparatus of the character described comprising a tank, a plurality of perforated partitions extending across the interior of said tank and dividing the same into a plurality of compartments, the lowermost of said partitions located at a distance from the bottom of said tank substantially less than the height of any of said compartments, and forming a gas-distributing chamber, means connecting said chamber to gas-receptacles,

overflow-pipes connecting each of said compartments to the compartment therebelow, the overflow-pipe of the lowermost compartment leading to a receptacle for acid, an exhaust-pipe, and a supply-pipe connected to the uppermost compartment, and means to agitate the contents of said compartments.

2. An apparatus of the character described comprising a tank, a plurality of perforated partitions extending across the interior of said tank and dividing the same into a plurality of compartments, the lowermost of said partitions located at a distance from the bottom of said tank substantially less than the height of any of said compartments, and forming a gas-distributing chamber, means connecting said chamber to gas-receptacles, overflow-pipes connecting each of said compartments to the compartment therebelow, the overflow-pipe of the lowermost compartment leading to a receptacle for acid, an exhaust-pipe, a supply-pipe connected to the uppermost compartment, a shaft extending longitudinally of said tank through said compartments, agitator-blades fast to said shaft in each of said compartments, and mechanism to impart a rotary motion to said shaft.

3. An apparatus of the character described comprising a tank, a plurality of perforated partitions extending across the interior of said tank and dividing the same into a plurality of compartments, the lowermost of said partitions located at a distance from the bottom of said tank substantially less than the height of any of said compartments and forming a gas-distributing chamber, a pipe connecting said chamber to a gas-receptacle, said pipe extending upward from the bottom of said tank to a distance sufficient to prevent the liquor therein from flowing into said gas-receptacle, overflow-pipes connecting each of said compartments to the compartment therebelow, the overflow-pipe of the lowermost compartment leading to a receptacle for acid, an exhaust-pipe, and a supply-pipe connected to the uppermost compartment, and means to agitate the contents of said compartments.

In testimony whereof I have hereunto set my hand in presence of two subscribing witnesses.

ELLIOTT R. BARKER.
